MULTIPLE COMPARTMENT REFRIGERATOR

Luther C. Lollis, Waterloo, S. C.

Application September 19, 1956, Serial No. 43,000

Term of patent 3½ years

(Cl. D67—3)

The figure is a perspective view of the multiple compartment refrigerator with some of the doors shown in open position.

The rear portion of the refrigerator which is not shown is substantially identical to that portion which is shown.

I claim:

The ornamental design for a multiple compartment refrigerator, as shown and described.
